UNITED STATES PATENT OFFICE.

CARL F. PEARSON, OF CHICAGO, ILLINOIS.

OIL-BURNING SYSTEM AND APPARATUS.

Application filed November 13, 1923. Serial No. 674,473.

To all whom it may concern:

Be it known that I, CARL F. PEARSON, a citizen of the United States, residing at Chicago, in the county of Cook and State 5 of Illinois, have invented certain new and useful Improvements in Oil-Burning Systems and Apparatus, of which the following is a specification.

The invention relates to oil burning systems and apparatus.

One of the objects of the invention is to improve systems of this character.

Another object is to perform all of the functions necessary for convenience, safety 15 and economy with simplified apparatus.

Another object is to provide a system in which the oil is agitated and mixed with air before it reaches the burner.

A further object is to provide means, 20 whereby oil taken from a supply tank, in excess of that used by the burner, is automatically divided and returned to the tank by effect of the pump that causes the oil to flow from the tank.

A further object is the provision of means for varying the pressure on the oil forced into the burner by restricting to a greater or less extent the flow of oil through the oil return pipe.

Other objects and advantages will hereinafter appear from a consideration of the following description, when taken in conjunction with the drawings, wherein:

Fig. 1 shows an end elevation, part in section, of the oil pumping plant comprising a part of the system.

Fig. 2 is a vertical transverse section taken through the air pump and air intake valve.

Fig. 3 shows a plan view of the system.

Fig. 4 is a side elevation of the plant showing a furnace in section.

Fig. 5 is a central vertical section thru the oil atomizer and burner.

Fig. 6 is a transverse section on line 6—6 of Fig. 5.

Fig. 7 is a longitudinal central section thru the burner showing an air siphoning conduit surrounding it.

Fig. 8 is a loose coupling between the motor shaft and the pump shafts.

Fig. 9 is a section thru a regulable valve to control the oil supply furnished to the burner.

Fig. 10 is an end elevation of the same showing means for its automatic control.

Fig. 11 is a side elevation, part in section,

showing the automatic gas and oil controlling device.

Fig. 12 is a section on line 12—12 of Fig. 11.

In all the views the same reference characters refer to corresponding parts.

The drawings show three main features, the oil supply tank 15 which may be buried in the ground outside of the premises; an oil pumping plant which for convenience should be located near the furnace, and the furnace 17.

The pumping plant consists of an electric motor 18 mounted upon a base plate 19. Under the base plate is an oil drip pan 20 having, preferably, an inclined floor 21, the deepest portion being near the end of the air intake pipe 22.

The base 19 may be mounted on the table 23, or other suitable support near the furnace. Mounted on the base plate 19 is an air compressing pump 24 having its shaft 25 coaxially in line with the shaft 26 of the motor. These shafts are coupled together by a loose coupler 27.

The oil supply pump 28 and the air supply pump 24 are more specifically set forth and claimed in my copending application Serial No. 549,815, filed April 5, 1922.

The oil pump and the air pump axes are in alignment with the motor shaft and are driven at the same speed. Both pumps are of the pressure type and will produce pressure substantially within the capacity of the motor.

The intake 29 of the oil pump 28 is connected by pipe 30 to the oil supply tank 15, which extends to the bottom of the tank and which carries a strainer and foot valve 31 on its lower end.

Another strainer 32 may be used to more completely purify the oil before it reaches the burner 33.

The oil supply pump 28 discharges into pipe 34 and into the oil return pipe 35. In the oil return pipe 35 is placed a regulable check valve 36 which is similar to the regulable check valve 37, placed at the inner end of the air intake pipe 22 and which is to be more fully described.

The lower end 38 of the check valve 37 is connected to air intake pipe 22 and the part 39 is connected to the intake 40 by a close nipple 41. The incoming air from pipe 22 due to the suction of the pump 24 passes thru the port 42, which is normally closed

by the spring-pressed valve 43. The spring 44 yieldingly holds this valve closed. A screw 45 regulates the strength of the spring for a purpose to be described.

5 Extending laterally from the neck 39 of the valve 37 is a hollow, internally threaded boss 46 to receive the pipe 34.

A needle valve port 47 connects the interior of pipe 34 with the interior of the 10 valve 37. This port may be closed by the needle valve 48. The valve 48 is made on the inner end of the reciprocatable stem 49 and is held yieldingly and normally closed to stop flow of oil to the burner when the 15 pumps are not in operation by a spring 50. The valve may be opened to an extent limited by a shoulder 51 on the valve stem 49 striking the end of the reciprocatable threaded sleeve 53.

20 The sleeve 53 may be rotated by the thumb nut 52 or by the lever 56 to vary the pre-determined extent of opening of said valve. A check nut 55 may be used to hold the sleeve in adjusted position. An arm 57 may 25 also be used to automatically regulate the extent of opening the valve 48 by variation of temperature thru suitable thermo-responsive means, in which event the use of the check nut 55 will be dispensed with.

30 In Fig. 10 I have shown the arm 56 connected by a link 57 to a lever 58 which is pivoted at 59 and which is connected to a pressure pressed diaphragm 60 by a link 61. The diaphragm covers a casing 62 35 which may be connected to a boiler or the like by pipe 63.

When the diaphragm bulges out, by increased steam pressure, the sleeve 53 is rotated to the right and the valve 48 moved towards its port. When the pressure subsides the valve is correspondingly opened to increase the flow of oil to the burner. The arrangement shown in Fig. 10 need only be used when it is desirable to maintain 45 temperature or steam pressure constant by increasing and decreasing the consumption of oil accordingly.

The electric motor 18 is energized by current over wires 64 and 65. Associated with 50 a circuit containing the motor is an electro-magnet or solenoid 66, energized from the same source, so that when the circuit has been opened thru the motor the electro-magnet is energized.

55 An armature 67 is pivoted at 68 to a lever 69, pivoted at 69^a, and is movably responsive to the electro-magnet 66. Its arm 69' is connected to the reciprocatable valve stem 49 by the rod 49'. It will, therefore, be 60 apparent that when the electric motor 18 is deenergized, so likewise will be the electro-magnet 66, and the valve 48 will be automatically closed by the spring 50 and instantly stop flow of oil to the burner 33.

65 When the motor is energized the valve 48

will be opened by the electro-magnet 66 before the pumps can be started in operation by the motor. The electro-magnet, or solenoid, 66 also controls the gas supply to the pilot light, to be presently explained.

The quantity of oil which will flow back to the oil supply tank 15 thru the return pipe 35 will depend largely upon the relative adjustment of the spring 50 in valve 36 and the opening of the port 47 by valve 48. In any event the oil pumped by the pump 28, which does not pass out of port 47 to the burner 33 is automatically returned to the supply tank.

7 After oil from pump 28 passes thru port 47 it is discharged into the air intake conduit 39, 40 and 41, and into the air pump 24 and by it, with the air taken in thru pipe 22 and the check valve 37, it is conducted, under pressure, to the burner 33 thru 80 pipe 70.

85 Connected to pipe 70 is a pressure gage 71 which shows the pressure under which the mixed air and oil is subjected as it is delivered to the burner. The oil is broken up and mixed with the air while passing thru the air pressure pump 24.

90 The air intake pipe 22 extends into the oil drip pan 20 so as to take up, with the incoming air, any waste oil that may have leaked from the pumps and been caught in the pan. Screens 72 are placed over the 95 openings above the pan to keep out all foreign undesirable matter. By this means oil that would otherwise be wasted is utilized 100 in the burner by being drawn up into pipe 22 with the air and the plant remains clean.

105 The burner 33 consists, as shown, of a casing 73 having an angularly related, hollow, threaded boss 74, to receive the oil and air conducting pipe 70. An axial, hollow boss 75 extends into the casing, as at 76, its outer end being internally threaded to receive a plug 77. The front end of the casing is closed by a relatively thin wall 78 110 having an outwardly flaring, central port 79 for a self closing valve 80. The valve 80 is the terminal end of the reciprocatable valve stem 81. The rear part of the stem is enlarged and angular in cross section, as shown in Fig. 6, to provide openings in the bore of the inwardly extending boss 76 and the stem to admit air, under pressure, in the opening 82 to unseat the valve 80 115 against the effect of the spring 83, which tends always to close the valve. The stem is provided on its rear end with a guiding head 84 to maintain the stem in central position of the bore and enlarged opening. One end of spring 83 contacts this head and the other end contacts the shoulder in boss 76 provided by enlarged opening 82 and the coaxial bore in the end of 76. It is now manifest that when the valve is closed, air 120 under pressure in the casing 73, will unseat 125

the valve by compressing the spring 83 and when there is no air pressure within the casting the spring 83 will automatically close the valve.

5 In Fig. 7 I have shown the burner 33 surrounded with a spaced jacket 85 to leave an air conduit between the burner and the jacket for the purpose of drawing fresh air into the furnace, near the point of combustion of the burner, to promote and enhance combustion and to decrease the noise resulting therefrom.

I have also improved the fire box construction with the same end in view.

15 On the grate 86 I lay a floor of fire brick or tile 87 and place a vertical wall 88 inside the fire box to protect the metal portions from the destructive effects of the flame projected from the burner. I erect 20 wall 89 in front and leave a space 90 so that air may pass upwardly from the ash box to the burner.

I cover part of the wall 88 with a dome piece 91 to produce a closed chamber 92 into which the flame is projected and in which complete combustion is attained. A gas pilot light is provided by the pipe 93. The pipe 93 for furnishing the pilot light is an extension of the gas pipe 94. A gas 30 controlling valve structure 95 is connected in the gas pipe 94. A ball check valve 96 is supported by a spring 97 to normally close the port 98 thru which gas passes on its way to the burner. A reciprocatable 35 stem 99 bears normally against the under surface of the arm 69^b, of the lever 69, so that when the lever 69 is raised by the solenoid 66 the gas valve is thereby opened and when the solenoid and the motor are 40 deenergized the valve controlling the oil supply and the valve controlling the gas supply will be closed and the fuel shut off from the burner.

From the foregoing description the operation of the system will be clearly understood, but a brief résumé may contribute to a clearer disclosure.

To start the system primarily in operation the electric circuit is closed, which energizes electro-magnet 66, and the gas pilot light is then ignited. Closing said circuit also closes the electric circuit thru the motor 18. When energized the electro-magnet 66 immediately opens valve 48 by its armature 67 pulling out the valve stem 49 against the yielding effect of the spring 50. The magnet will move the shoulder 51 of the stem into contact with the end of the threaded sleeve 53 and open the valve to a predetermined extent; the motor 18 begins to revolve and the pumps to operate. The oil pump 28 pumps an excess supply of oil from the bottom of tank 15 thru pipe 30 and strainer 32 into pipes 34 and 35. Part of the oil from pipe 34 will pass thru port 47

into pipe or conduit 39, 40 and 41, leading to the air pump 24.

The oil automatically divides between pipe 34 and pipe 35. The excess of oil will be returned to the supply tank 15 thru 70 regulable valve 36 and return pipe 35, the division is inversely proportional to the respective resistances interposed, to some extent, by the respective adjustments of the check valve 36 and the needle valve 48 75 of 37.

The air pump 24 draws air thru pipe 22 thru regulable check valve 43 into conduits 39, 40 and 41 where it meets the oil from the oil pump 28. It also assists 80 to draw oil in thru valve 48.

The air and oil is agitated and mixed in air pump 24 and directed, under pressure, about 5 lbs. per square inch, thru pipe 70 to the burner 33.

The effect of the internal pressure in the burner casing, as heretofore explained, opens the burner valve 80, whereupon the mixed air and oil in an atomized state is projected into the chamber 92, the spray being ignited 90 by the gas pilot flame from pipe 93.

When the fire brick structure, within the furnace, becomes heated to a visible degree combustion is therein completed and carbon from the flame cannot be set free and smoke formed as when the flame is allowed to impinge directly upon relatively cold surfaces or when it is mixed with cold air. The flame passing into the chamber 92 produces a reverberatory effect by being reflected back thru the opening thru which it came, which increases its contact surface with the bricked structure. The coupling 27, connecting the motor shaft with the pump, will form the subject matter of an 105 application to be hereafter filed.

Having described my invention what I claim as new and desire to secure by Letters Patent, is:—

1. An oil burning system including an oil supply tank; an oil burner; a pilot burner; an oil supply pump between said tank and oil burner; an air pump connected to said oil pump; means for conveying oil from said tank to said oil burner thru said pumps; an electro-magnetically controlled valve between said pumps for controlling the flow of oil to the burner; said electro-magnetic means also controlling the supply of fuel to said pilot burner; and an oil return pipe between said pumps to return any excessive supply of oil to said tank.

2. An oil burning system including an oil supply tank; a boiler, a burner therefor; an oil supply pump between the tank and burner; a controllable normally closed valve between the pump and burner to control the flow of oil to the burner; electro-magnetic means for opening said valve; adjustable means automatically controlled by the 130

boiler pressure to vary the extent to which the valve can be opened; automatic means to close the valve when the magnetic means is deenergized; and an oil return pipe connected between the oil pump and the valve and to the tank to return the excess of oil not used in the burner to the tank.

3. An oil burning system including an oil tank; a burner; an oil supply pump connected to the tank; an air supply pump connected to the burner and to the oil supply pump; a needle valve between the pumps normally closed when the pumps are in-

operative; means to open said valve when the pumps become active; a spring seated 15 regulable air intake check valve controlling the air admitted into the air pump; an oil return pipe connected between the oil pump and the needle valve and to the tank and a spring seated regulable valve in the 20 return pipe to vary the quantity of oil passing thru said needle valve.

In testimony whereof I hereunto subscribed my name.

CARL F. PEARSON.
